United States Patent Office.

R. P. HENRY, OF AKRON, OHIO.

Letters Patent No. 71,386, dated November 26, 1867.

IMPROVEMENT IN ROOFING.

The Schedule referred to in these Letters Patent and making part of the same.

TO ALL WHOM IT MAY CONCERN:

Be it known that I, R. P. HENRY, of Akron, in the county of Summit, and State of Ohio, have invented a new and improved Roofing; and that the following description, taken in connection with the accompanying drawing hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention relates to a new and improved means for keeping the joints of board or plank roofing perfectly tight and weather-proof; and it consists in having the joints of the boards or planks covered by a sheet-metal strip, the edges of which are bent down and fitted in grooves in the boards or planks, vertical plates or break-waters being also inserted in the grooves, and the whole covered by a wooden batten, as hereinafter fully shown and described, whereby a perfectly weather-proof roof of the kind specified is obtained. In the accompanying sheet of drawings—

Figures 1 and 2 represent transverse sections of my improvement.

A represents a lath of the roofing, to which the boards or planks B are secured by nails in the usual or any proper manner. Over the abutting edges of the boards or planks there are placed sheet-metal strips C, the edges of which are turned or bent down, and driven in grooves, as shown clearly at *a* in both figures. These sheet-metal strips cover the joints of the boards or planks. D represents sheet-metal strips, which are driven in the same grooves as the edges of the strips C. The strips D have a vertical position, and extend upward considerably above the upper surfaces of the boards or planks. These strips serve as break-waters, and effectually prevent any water from finding its way to the joints. The upper parts of the strips or break-waters D and the strips C are covered by battens E, which may be nailed or screwed down upon the boards or planks. The grooves in the battens which receive the strips or break-waters D are designed to be sufficiently wide to admit of the shrinking of the battens, boards, or planks.

I do not claim separately the strips C, nor the battens E; but I do claim as new, and desire to secure by Letters Patent—

The vertical strips or break-waters D, fitted in grooves in the boards or planks B, and projecting above the upper surfaces of the same, in connection with the battens E, substantially as and for the purpose set forth.

I further claim the combination of the battens E, strips C, and break-waters D, all arranged and applied to the boards or planks B, substantially as and for the purpose specified.

R. P. HENRY.
